DESIGN FOR AN APRON

Frances Young Wilson, Larchmont, N. Y.

Application December 31, 1940, Serial No. 97,738

Term of patent 7 years

To all whom it may concern:

Be it known that I, Frances Young Wilson, a citizen of the United States and a resident of Larchmont, in the county of Westchester and State of New York, have invented a new, original, and ornamental Design for Aprons, of which the following is a specification, reference being had to the accompanying drawing, forming part hereof.

The drawing shows an elevational view of an apron embodying my new design.

The characteristic feature of my design resides in the combination, on the specific apron disclosed, of the specific ornamentation arranged as shown.

I claim:

The ornamental design for an apron, as shown and described.

FRANCES YOUNG WILSON.
